SHOE-VAMP BLANK

Arthur C. Engel, Haverhill, Mass.

Original application March 25, 1948, Serial No. 16,948. Divided and this application January 24, 1949, Serial No. 72,285

4 Claims. (Cl. 36—47)

1

The present invention relates to shoe-vamp blanks. This application is a divisional application of my parent application, Serial No. 16,948, filed March 25, 1948.

An object of the present invention is to provide a new and improved shoe-vamp blank adapted to be molded to finished shoe vamp shape before assembly in a shoe.

Other and further objects will be explained hereinafter and will be particularly pointed out in the appended claims.

The invention will now be more fully explained in connection with the accompanying drawings, in which Fig. 1 is a perspective of a shoe embodying the invention; Fig. 2 is a fragmentary perspective, partly in section, of a modification; Fig. 3 is an elevation of a stiffener blank of the present invention out of which may be manufactured the prepared molded shoe vamp shown in Fig. 2; Fig. 4 is a similar elevation showing the stiffener blank of Fig. 3 assembled with an inner lining and an outer leather covering; Fig. 5 is a similar elevation of a similar stiffener blank constituted wholly of leather; Fig. 6 is an elevation of the stiffener blank shown in Fig. 3; Fig. 7 is a vertical section taken upon the line 7—7 of Fig. 4, looking in the direction of the arrows; Fig. 8 is an elevation of the leather stiffener blank shown in Fig. 5; Figs. 9, 10 and 11 are elevations similar to Figs. 3 and 5 of further modified stiffener blanks; and Fig. 12 is a section similar to Fig. 7 of the blank of Fig. 11, the section being taken upon the line 12—12 of Fig. 11, looking in the direction of the arrows.

A prepared molded shoe vamp embodying a shoe-vamp blank of the present invention is shown in Fig. 1 provided at its extreme toe portion and on both sides 15 thereof with a portion 6 rising upward a short distance from the outer edge 1 of an inturned bottom flange 16. A tongue 13 rises a substantial distance upward from the upwardly rising portion 6 at its extreme toe portion, and front vamp tongues 17 and rear vamp tongues 19 rise similarly a substantial distance upward from the upwardly rising portion 6 on both sides 15 of the extreme toe portion. This style of prepared shoe vamp may be manufactured from a flat blank 12 having the general shape illustrated, for example, in Fig. 9. The tongue 13 is replaced in Fig. 9, however, by a tongue 9 of more slender shape and longer than the tongue 13, and the portion 6 is shown rising upward a little higher than in Fig. 1. The toe portion may, on the other hand, be of smaller length, as shown by the blank 47 of Fig. 10, and

2

it may be even smaller still, as shown by the blank 48 of Figs. 11 and 12. The tongue 9 or 13 is shown disposed approximately centrally of this blank 12, and the front vamp tongues 17 and the rear vamp tongues 19 are disposed between the center and the ends of the blank.

Other styles of shoe-vamp blanks are, of course, possible. The rear side-portion tongues 19 of the vamp of Fig. 1, for example, may be omitted; or, on the other hand, the front side-portion tongues 17 may be omitted, instead; or both tongues 17 and 19 may be omitted; or the tongues 17 and 19 may be merged into a single continuous tongue, as described in the said parent application.

15 In the vamp illustrated by Fig. 2, as a further example, the portion 8 that is shown rising upward a short distance from the outer edge 1 of the inturned bottom flange 16 is not quite so long as the portion 6 of the vamp illustrated in Fig. 1. The side portions 15 thereof are shown 20 so relatively short as not to be able to provide support for any side-portion tongues 17 or 19. It is therefore provided with only the single tongue 13 rising a substantial distance upward from the 25 upwardly rising portion 8 at its extreme toe portion only. A shoe vamp of this shape may be manufactured from the blank illustrated, for example, in Figs. 3 to 8. In the leather stiffener blank of Figs. 5 and 8, the single tongue at the 30 extreme toe portion is indicated at 14.

In all cases, however, the upwardly rising portions of the shoe vamp molded from the shoe-vamp blanks of the present invention are separated at their upper edges in order to provide an opening at the top of the shoe vamp. The width of the vamp, at some approximately central point thereof, is in all cases small compared with its length, in order that this vamp opening shall extend from near the extreme toe portion 40 of the shoe vamp rearward throughout the length of the vamp. The tongues, such as are indicated at 9, 13, 14, 17 and 19, for example, project into this opening. A portion of the vamp formed from the blank 48 of Figs. 11 and 12 may similarly 45 rise upward to form a tongue portion in this opening.

The blank of the present invention out of which the vamp is manufactured may comprise a stiffener blank die or otherwise formed out of suitable sheet material. Several such blanks are illustrated in Figs. 3 to 8 and 9 to 12. The sheet material may be constituted of composition, such as leatherboard, fiberboard or other vegetable-pulp product impregnated with sizing treated with wax or a similar substance. The margin of

the stiffener blank may be skived, as illustrated in Figs. 6, 7 and 12. The skiving is not, however, essential, and the leather stiffener blank of Figs. 5 and 8 is therefore shown unskived.

The flat stiffener blank may be secured in place between a flat inner lining 28 and a flat outer cover 30 assembled therewith. The resulting shoe-vamp blank thus produced becomes provided with upper and lower edges 3 and 5, the lower edge 5 being adapted to define the inner edge of the inturned bottom flange 16 of the molded vamp. Each of these three component blanks extends upward from the lower edge 5, preferably along the complete length of the blank, and this provides the completed shoe-vamp blank with a main portion 6 or 8. The main portion is provided with the side parts 15 and a centrally disposed portion corresponding to the extreme toe portion of the vamp. The toe-portion tongue 9, 13 or 14 is shown supported by the centrally disposed portion of the blank at a substantial distance from the ends of the blank. The width of the blank between the upper and lower edges 3 and 5, at the sides of the tongue 9, 13 or 14, near the centrally disposed portion of the blank, is small compared with the length of the blank between its ends, and the width of the toe-portion tongue 9, 13 or 14 is short, thereby to provide the molded vamp with the previously described opening extending from near the extreme toe portion rearward throughout the length of the vamp.

The assembled shoe-vamp blank or the leather stiffener blank of Figs. 5 and 8 is molded into finished shoe-vamp shape in any desired manner, and it may also be wiped to form the inturned bottom flange 16, as is well known in the art. The inturned bottom flange 16 may be slashed, as shown at 25, prior to the molding and wiping operations.

The vamp is then ready for assembly in a shoe. In Fig. 2, as an illustration, it is shown assembled by securing the inturned bottom flange 16 between the outer sole 2 and the inner sole 4 at the toe portion and on both sides of the shoe by means of staples 45. No lasting operation is at all required during this assembly, though a last may be employed as a support for nailing or cementing.

An advantage of the present invention is that it is not necessary to manufacture shoes embodying molded shoe-vamp blanks in so many sizes and shapes as has heretofore been the practice; for any shoe embodying the invention will fit many feet of varying size and shape.

In Fig. 1, for example, a shoe lace 34 is illustrated as threaded through eyelets 36 in the toe-portion tongue 13 and the side-portion vamp tongues 17 and 19, and it may be tensioned or tightened in varying degrees so as to cause the toe-portion tongue 13 and the side-portion vamp tongues 17 and 19 to bind against the foot with suitable pressure, after which the shoe lace 34 may be tied into a knot, as illustrated in Fig. 1, or it may be carried back of the ankle, or it may be fastened in any other desired way. In order to facilitate the adjustment, the toe-portion tongue 13 and the side-portion vamp tongues 17 and 19 of the stiffener blank may, instead of rising co-extensively with the inner lining and the outer covering, be wholly omitted, as illustrated in Figs. 10 to 12, though without omitting the corresponding toe-portion tongue and side-portion vamp tongues of the inner lining 28 and the outer leather covering 30.

For women's shoes embodying the shoe-vamp

blanks of the present invention when molded, the height or width above the bottom flange 16 of the portions of the vamp between the tongues may vary from a small fraction of an inch, as illustrated, for example, at the extreme forward portion of the vamp illustrated in Fig. 12, to a maximum of about an inch. The maximum width of the unmolded blank between its bottom edge 5 and the portions 3 of the upper edge of the blank between the tongues would then be about an inch and a quarter in order to provide for a quarter-inch flange 16. The length of the bottom edge 5 of the unmolded blank may be about six or seven inches. A half-inch height or width above the outer periphery of the bottom inturned flange 16 of the vamps is illustrated, for example, in Fig. 1. In Figs. 3 to 8, as a further illustration, the half-inch height or width is indicated as extended to the outer ends of the blank.

Further modifications will occur to persons skilled in the art, and all such are considered to fall within the spirit and scope of the invention, as defined in the appended claims.

What is claimed is:

1. A shoe-vamp blank adapted to be molded to finished shoe-vamp shape before assembly in a shoe, the blank comprising, in unmolded state, a flat inner lining assembled with a flat outer covering and a flat stiffener inserted therebetween, the blank having upper and lower edges, the inner lining, the outer covering and the stiffener all extending upward from the said lower edge and along the complete length of the blank to provide the blank with a main portion, the inner lining, the outer covering and the stiffener being substantially coextensive with one another throughout the main portion of the blank, the blank having separated tongues positioned intermediate the ends of the blank and extending a substantial distance upward above the main portion of the blank, and the width of the blank between the said upper and lower edges being small compared to the length of the blank between its ends.

2. A shoe-vamp blank adapted to be molded to finished shoe-vamp shape before assembly in a shoe, the blank comprising, in unmolded state, a flat inner lining assembled with a flat outer covering and a flat stiffener inserted therebetween, the blank having upper and lower edges, the inner lining, the outer covering and the stiffener all extending upward from the said lower edge and along the complete length of the blank to provide the blank with a main portion, the inner lining, the outer covering and the stiffener being substantially coextensive with one another throughout the main portion of the blank and forming separated tongues positioned intermediate the ends of the blank and extending a substantial distance upward above the main portion of the blank, and the width of the blank between the said upper and lower edges being small compared to the length of the blank between its ends.

3. A shoe-vamp blank adapted to be molded to finished shoe-vamp shape before assembly in a shoe, the blank comprising, in unmolded state, a flat inner lining assembled with a flat outer covering and a flat stiffener inserted therebetween, the blank having upper and lower edges, the inner lining, the outer covering and the stiffener all extending upward from the said lower edge and along the complete length of the blank to provide the blank with a main portion, the inner lining, the outer covering and the stiff-

ener being substantially coextensive with one another throughout the main portion of the blank, the inner lining and the outer covering extending a substantial distance upward above the main portion of the blank to form separated tongues positioned intermediate the ends of the blank, and the width of the blank between the said upper and lower edges being small compared to the length of the blank between its ends.

4. A shoe-vamp blank adapted to be molded to a finished shoe-vamp shape before assembly in a shoe, the blank comprising, in unmolded state, a flat inner lining assembled with a flat outer covering and a flat stiffener inserted therebetween, the blank having upper and lower edges, the 15 inner lining, the outer covering and the stiffener all extending upward from the said lower edge and along the complete length of the blank to provide the blank with a main portion, the inner lining, the outer covering and the stiffener being 20 substantially coextensive with one another throughout the main portion of the blank, the

blank having separated tongues positioned intermediate the ends of the blank and extending a substantial distance upward above the main portion of the blank, the width of the blank between the said upper and lower edges being small compared to the length of the blank between its ends and the tongues having means for receiving means for placing the tongues under varying degrees of tension.
